M. PALMER.
TOY AIRPLANE.

APPLICATION FILED JAN. 27, 1922.

Patented Apr. 11, 1922.

2 SHEETS—SHEET 2.

UNITED STATES PATENT OFFICE.

MONTAGUE PALMER, OF TENAFLY, NEW JERSEY.

TOY AIRPLANE.

1,412,418.

Specification of Letters Patent. Patented Apr. 11, 1922.

Application filed January 27, 1922. Serial No. 532,348.

To all whom it may concern:

Be it known that I, MONTAGUE PALMER, a citizen of the United States, residing at 43 Norman Place, Tenafly, county of Bergen, and State of New Jersey, have invented new and useful Improvements in Toy Airplanes, of which the following is a clear and exact specification, reference being had to the drawings which form a part

10 of the specification.

This invention relates to toy airplanes and my improvements are particularly directed to novel means of construction of the parts employed therein whereby a toy airplane 15 may be conveniently and readily assembled for use, and disassembled for packing and transportation.

My invention is characterized in one of its features by having a fuselage which is 20 built up of four longérons which are to be assembled, in spaced, quadrilateral form, and united by means of a series of rectangular bulkheads, composed of thin sheet metallic material.

25 The longérons are respectively provided with opposite slits or incisions at predetermined points in their length, for the embedment therein of the bulkheads, at their respective corners, to thus serve as localizing 30 means in the longitudinally spaced arrangement of the bulkheads relatively to the fuselage. The bulkheads also have free end portions or tabs that are capable of folding over upon the longérons to securely 35 unite these parts.

A further feature of invention comprehends the wing construction, which includes ribs of thin sheet metallic material, flanged at their upper and lower edges to 40 increase their rigidity, and apertured to receive the beams, which latter are provided with slits or incisions at predetermined points in their length for the embedment 45 therein of the ribs, to thus serve as localizing means. The ribs are symmetrical in their chordwise curvature to be capable of interchangeable employment.

Sheathing for the fuselage also comprises a feature of my invention, with 50 spaced elements extending transversely thereof, which also serve as guides for the wing beams and as means for securing the sheathing to the fuselage frame-work.

Other features and advantages of my invention will hereinafter appear.

In the drawings:

Figure 1 is a top plan view of a toy airplane embodying my improvements.

Fig. 2 is an enlarged section on the line 2-2 of Fig. 1 showing a bulkhead in end view thereof.

Fig. 3 is a similar section on the line 3-3 of Fig. 1 showing the spacer means for the fuselage sheathing.

Fig. 4 is a side elevation, partly broken, 65 away, of my toy airplane.

Fig. 5 is a perspective elevation of the radiator.

Fig. 6 is a perspective elevation of the fuselage front end. 70

Fig. 7 is a section on the line 7-7 of Fig. 6.

Fig. 8 is a perspective elevation of the fuselage rear end.

Fig. 9 is a fragmentary side elevation of a wing rib.

Fig. 10 is a detail of an anchorage fitting for the tension wires, and Fig. 11 is a detail view showing the means of connecting the vertical rudder to the rear fitting. 80

The fuselage or body portion of my improved toy airplane is composed of the four longérons 1, arranged in quadrature, and engaged, respectively, at the corners of a series of bulkheads 2, which are disposed transversely of the structure. The bulkheads 2 are composed of thin sheet metallic material, and are of open or frame-like character, the outer edge being formed into a right angular flange 3 to impart a degree 90 of stiffness or rigidity to the structure. At the respective corners of the bulkheads rectangular recesses 4 are provided for the reception of the longérons 1, extended portions or tabs 5 of the flange 3 being adapted to fold over upon the longérons, to clamp them into engagement with the bulkheads. 95

Also the longérons are each provided upon respective inner sides thereof with slits or indentations 6, for the reception of outer 100 edge portions of the bulkheads, to localize the bulkheads, relatively to the longérons, lengthwise of the latter.

One of the purposes of my invention is to provide for the production of all the 105 separate elements necessary in the construction of a toy airplane in such manner that these elements may be easily put together with expedition and accuracy and securely united in the ultimate structural form, with-

out the aid of tools or extraneous fastening means.

The fuselage or body framework, thus far described, is typical of the means devised by me in carrying out this purpose. At their front ends the longérons 1 engage respectively with the four corners of a head plate 7, fitting in sockets provided for their reception by turning over the upper, lower and side portions of plate 7, and by the provision of tongues 8 that are struck from the plate 7 and are folded over upon the longérons respectively. The plate 7 itself serves as a forward end abutment for the longérons.

The plate 7 has lugs 9 struck therefrom and projected outwardly, and an element 10, shaped to resemble a radiator, and adapted to fit over plate 7, has apertures 11 for the reception of lugs 9, which may be bent over, outside element 10, to clinch it to plate 7.

A rear fitting 12, composed of sheet metallic material, is shaped to provide the upper and lower channel portions 13, 14, for the reception respectively, of the converged ends of the upper and lower pairs of longérons, while the material of fitting 12, at opposite sides thereof, is bent inwardly to comprise a spacer 15 separating the upper and lower longérons. It will be appreciated, in this structural form of fitting 12, that its rear wall serves as a terminal abutment for the longéron ends.

Sheathing 16, in the form of a thin sheet of metallic material, is fitted over the top and sides of the frame, at its forward portion, including a representation of a cockpit and engine housing.

The rearward edge of sheathing 16, is adapted to be inserted between the longérons and the flange 3 of one of the bulkheads 2, to connect it with the frame, said sheathing also having tabs 17 at its forward side edges, to fold under the lower longérons.

Further means of securing the sheathing to the frame comprises the pairs of plates 18, with bolts 19, the plates of a pair lying respectively outside the sheathing and against the inner surface of an adjacent longéron, the union being effected by engaging the plates 18 with bolts 19 which extend respectively across the upper and lower surfaces of a longéron, the upper bolt being passed through an orifice provided therefor in the sheathing.

Spacer devices for the sheathing, which, as will be hereinafter described, also serve as anchorage for the wing beams, consist of hollow members 21 produced by folding thin sheet metallic material into rectangular form, with end extensions 22 adapted to project outwardly through rectangular orifices 23 provided in the side walls of sheathing 16, and to be turned over against the outer surfaces of the respective walls, to

localize the spacers between said walls. Also the spacers have shoulder portions 23^a that lie close up against the inner surfaces of the respective walls, thereby enabling the spacers to serve as compression members, 70 to prevent the collapse of the sheathing walls.

The wings, generally indicated by the reference character 24, are composed of the beams 25, which are rectangular in cross-section, and provided with transverse slits 26 at various points along their length.

Ribs, 27, formed of thin sheet metallic material, and provided with upper and lower flanges, 28, 28^a, respectively, to accord them 80 a stiffening channel-like section, each has rectangular orifices 29 in its web portion to receive the beams. The webs of the rib members, at the upper portions of the orifices 29, are adapted to enter the slits 26 in 85 the beams, and tabs 30 cut out from the lower portions of the orifices 29, are adapted to be folded up against the bases of the beams to thereby secure them in their engagement with the ribs. By these means 90 the ribs are localized in set positions relatively to the beams.

The ribs are provided with symmetrical curvatures toward opposite ends in order that the ribs may be used interchangeably 95 with wings at either side of the fuselage, the curvatures at the upper surfaces of the ribs meeting the straight plane base thereof, and, at the respective ends of the ribs, where the flanges 28, 28^a come together, are provided with means for the reception of a wire 100 31 which extends around the perimeter of the wing. The wire has its opposite ends engaged in apertures 32 provided upon a rib lying next the fuselage, a wire 31 extending 105 therefrom continuously about the wing and lying in end recesses provided at outer terminal points of the beams, whereby there is produced a compact wing frame structure.

The beams project beyond the ribs which 110 lie next the fuselage, and the projecting portions of the beams are adapted to enter the hollow members 21 which serve as sheathing spacers; said beam ends, for the opposite wings, having abutting relation within 115 the spacers, by which they are mounted in the assembled positions of the wings.

Tension wires 33, provided for the purpose of securing the wings to the fuselage, and stiffening the union between these elements, are secured in position as follows:—

A bifurcated mast composed of a strip of thin sheet metallic material folded upon itself to constitute its upper end, and provided with the legs 34, is adapted to straddle 125 the fuselage, over the sheathing 16, and directly above the opening or clearance 35 which is representative of a cockpit, the opposite ends of these legs lying against the respective opposite outer surfaces of the 130

sheathing. The legs are secured to the fuselage by means of pairs of clamping plates 36, and bolts 37, that respectively pass above and below the upper longérons, for securing the mast to the structure. The mast is provided at its upper end with orifices for the reception of the upper tension wires 33.

Also, anchorage means for lower tension wires 38 consist of a strip 39 of thin sheet metallic material disposed between the lower pair of longérons, and having end portions which project outwardly, with engaging eyelets 40. End portions of these strips 39 are shaped angularly to abut against the opposed inner surfaces of the opposite longérons, and to lap over the upper surface thereof, as indicated at 41, whereby this strip 39 also serves as a reinforcing spacer member for the longérons of the frame structure.

I have devised a special form of fitting for engagement with a rib upon each of the wings to comprise anchorages for the outer ends of the tension wires 33, 38. These fittings, (see detail view, Fig. 10) consist each 25 of thin sheet metallic material shaped to comprise the socket portion 42, to fit over the lower rib portion; the socket portion 43 to straddle a beam, the upper, forwardly inclined portion 44 with an engaging orifice 30 for an upper wire, and an inwardly extended lower portion 45 with engaging means for a lower tension wire.

One of these fittings is applied to each beam of the wing, and the respective tension wires, when strung between the fittings and the mast and between the fittings and the lower anchorage eyelets 40, serve to secure the wings to the fuselage with suitable tension.

The landing gear is composed of V-shaped hangers 46, disposed at opposite sides of the fuselage and secured at their upper ends thereto as by the fastening means 18, the axle 48 carrying the wheels 49, being mounted in the lower ends of the hangers.

The propeller, 50, carried by a spindle 51, is mounted thereby in a bearing 52 provided on the radiator, said spindle having a terminal hook 53 for engagement by a power member 54, whose other end is engageable with a hook 55, carried by a plate 56 that is fitted transversely of the fuselage, toward its rear end. The plate 56 has a rearwardly extended, upper flange 57, which is adapted 50 for the reception of the forward edge of the rear wing or elevator 58, to localize it in its set position upon the rear of the fuselage.

The vertical rudder 59, whose forward, lower edge 60 abuts against the rear surface 60 of fitting 12, overhangs the rear surface portion of elevator 58, to secure the latter upon the fuselage; and said rudder has at its edge 60 a pair of plate like fingers 61 which are adapted to be passed through a slit 62 in fitting 12 and to be bent over against the inner

surface of the fitting, to secure the rudder thereto.

Variations within the spirit and scope of my invention are equally comprehended by the foregoing disclosure:—

I claim:—

1. The combination, in a toy airplane, of a fuselage composed of spaced longérons, and bulkheads of sheet material disposed transversely thereof, the longérons having 75 slits for the edgewise localizing engagement of the bulkheads.

2. The combination, in a toy airplane, of a fuselage composed of spaced longérons, and bulkheads of sheet metallic material 80 disposed transversely thereof, the longérons having slits for the edgewise localizing engagement of the bulkheads, and the bulkheads having projecting portions to engagingly fold over upon the longérons.

3. The combination, in a toy airplane, of a fuselage composed of four longérons arranged in spaced quadrature, and bulkheads of flanged sheet metallic material disposed transversely thereof, the bulkheads having 90 corner recesses for the reception of the respective longérons, and projecting portions to engagingly fold over upon the longérons, and the longérons having slits for the edgewise, localizing engagement of the bulk- 95 heads.

4. The combination, in a toy airplane, of a wing therefor having a beam with a transverse slit, and a rib composed of flanged sheet metallic material, its web having an 100 orifice to receive the beam, the slit in the beam serving to localizingly engage the rib, edgewise, at its orifice, and the rib having a cut away portion at its orifice to securingly fold against the beam.

5. The combination, in a toy airplane, of a wing therefor having parallel beams, each with transverse slits, and a series of ribs composed each of flanged, sheet metallic material, their webs having aligned orifices, to receive the respective beams, the slits in the beams serving to localizingly engage the ribs, edgewise, at their orifices, and the ribs having cut away portions at their orifices to 110 securingly fold against the beams.

6. The combination, in a toy airplane, of a fuselage composed of longérons arranged in quadrature, sheathing therefor provided with opposite apertures in its side walls, a tubular member composed of folded sheet 120 metallic material extended between the side walls and serving for the reception of opposite, wing beams, the tubular members having shoulders to engage the inner surfaces of the sheathing walls, and end projections to clinch against the outer surfaces thereof.

7. The combination, in a toy airplane having a fuselage composed of upper and lower pairs of longérons, and opposite side wings 130

with beams and transverse ribs, of a bifurcated mast extending from and secured to the upper longérons of the fuselage, and a transverse compression member extended 5 between the lower longérons of the fuselage, the compression member having terminal projecting portions, fittings engageable with the wings, and tension wires extended respectively between the mast and fittings and 10 between the projecting portions of the compression member and the fittings.

8. The combination, in a toy airplane having a fuselage composed of longérons, of a

rear fitting comprising a plate with reception means for the longeron ends, the plate 15 having a vertical slit therethrough, and a vertical rudder adapted to lie against the plate, the rudder provided with a pair of metallic fingers adapted to penetrate the slit and to fold over against the rear surface of 20 the plate to secure the vertical rudder to the fuselage.

Signed at New York in the county and State of New York this 24th day of January, 1922.

MONTAGUE PALMER.
